UNITED STATES PATENT OFFICE.

SAMUEL J. SYMONS, OF SAN FRANCISCO, CALIFORNIA.

CASTING MACHINE.

Application filed July 21, 1922. Serial No. 576,530.

To all whom it may concern:

Be it known that I, SAMUEL JAMES SYMONS, a citizen of the United States, residing at 240 Stockton Street, in the city of San Francisco, in the county of San Francisco and State of California, have invented certain new and useful Improvements in a Casting Machine, of which the following is a specification.

10 This invention relates to metal casting machines and particularly to machines of the class known as "compressed air casting machines" designed to be used especially by dentists in the casting of inlays, saddles, 15 full and partial plates, and bridges, and said machines may be used by jewelers and others in the casting of small or comparatively small metallic parts.

It is customary to form such castings in 20 a mold cavity formed in a body of investment material contained in a flask, the metal being melted on the top surface of the investment and caused, partly by suction and partly by pressure, to accurately fill the 25 mold.

Difficulty has been experienced heretofore in the use of dental casting machines by which metallic inlays for teeth are formed, owing to the multiplicity of operations necessary during the process of molding the inlay or other article as the case may be.

The object of the invention is to provide a casting machine wherein the number of operations necessary on part of the person 35 making the mold and casting the inlay is reduced to a minimum so that the successful production of a casting is assured with a high degree of efficiency.

The invention is fully disclosed in the following specification, of which the accompanying drawings form a part, in which the separate parts of my improvement are designated by suitable reference characters in each of the views, and in which:

45 Figure 1 is a sectional view of my improved machine indicating the parts thereof in a normal position;

Fig. 2 is a side elevation of the machine showing the operative mechanism, parts of 50 the machine being omitted;

Fig. 3 is a top plan view of the flask supporting plate;

Fig. 4 illustrates a sectional view of the flask closing head for forming the matrice.

55 The machine illustrated in the drawings comprises a suitable supporting base or

foundation 1, carrying the stationary part of the machine, and which may rest upon a table or other support. On said base are mounted a flask supporting plate 2 and a vertically mounted cylinder 3, supported on the base 1 by an annular raised stand 4 securely attached to the base 1.

The flask support for the machine comprises a plate 5 mounted on four telescoping stems 6 sliding into four hollow standards 7 rising from the base 1. Surrounding each stem is a spiral spring 8 whose upper extremity bears against the plate 5, the lower extremity of the spiral spring engaging a shoulder 9 formed on the standards 7. The spiral springs thus positioned places the stems 6, together with the plate 5 supported thereby, under tension to move upwardly and permit of a limited rocking movement of the plate to automatically adjust itself when depressed into position by the flask as will presently be explained. (Only two of the said stems and standards being shown on the drawing.) A flask 10 is shown on Fig. 1, in operative position upon the plate 5. The central portion of the plate 5 being perforated as at 11 to facilitate a pre-heating of the flask by any suitable means, here not shown. The plate 5 is reduced at one end as at 12 and threaded therein is an adjustable releasing stem 13 having a suitable formed head 14 at its upper end. This releasing stem is designed to be manually raised or lowered, to retard or to accelerate respectively the release of the pawl 29 as will presently be explained.

The upper end of the cylinder 3 receives threaded thereon a cover 15 provided with an air valve 16, a pressure gage 17 and a flexible conduit 18. Arranged to operate within the said cylinder is a piston 19 having secured thereto and extending downwardly therefrom a metallic piston-band 20 slidably longitudinally through a collar 21 secured into the lower part of the cylinder. Surrounding the said piston-band within the said cylinder are two grouped or nested compression springs 22 and 22^a, the outer and inner coils of which are made with a different direction of helix to prevent binding of the same. The said spring 22 having bearing at one end against the piston 19 and at its other end against the collar 21, and the inner spring 22^a having bearing at its upper end within the piston skirt and at its lower end against said collar 21. The

object sought is to increase the carrying capacity within the given cylinder space. The said springs normally holding the piston in a raised position, while the lower end 5 of the piston-band 20 is attached to a revolving drum 23 secured to the shaft 24 journaled in suitable bearing ears 25 formed on the cylinder 3. A latching wheel 26 having an operating lever 27 is secured on 10 the outer end of shaft 24 for the purpose of turning said drum 23, winding the metallic band 20 around the same and thus depressing the piston 19 to an operative position. Means are provided for locking the 15 piston in this depressed position against the stress of the springs 22 and 22^a within the cylinder 3, and for this purpose a ratchet wheel 28 is secured to the opposite end of the shaft 24 acting in unison with the latching 20 wheel 26. A pawl 29, pivoted to a rearwardly extending bar 30, pivotally mounted on a standard 31 to the base 1, held normally in position by means of a tension spring 32, engages the notches on the ratchet wheel 28 25 to prevent return motion. To maintain the pawl 29 in proper cooperative relation to the ratchet wheel 28, a small coil spring means is provided as at 32^a, and with this construction the drum 23 will be locked 30 against the tension of the coil springs 22 and 22^a within the cylinder 3, until released.

A carrier 33, which is movable in a path parallel with the axis of the cylinder 3, is preferably a tube 34 slidably mounted in a 35 suitable guide 35 on the cylinder structure. To the lower end of the tube 34 is secured an outwardly flared cap 36 of such a size as to conform to the size of the flask 10. Detachably applied to the lower surface of the cap 36 is a disk 36' composed of asbestos or other suitable material adapted to seal the top of the flask 10. Surrounding the tube 34 and interposed between the guide arm 35 and the plate 37, is a coiled spring 40 45 39, normally urging the carrier to a raised or inoperative position as shown on Fig. 1.

It should be explained that the flask supporting plate of the structure is mounted to have a limited rocking movement to allow the flask 10 to automatically adjust itself when depressed by the sealing cap 36 during the time of operation.

To the upper end of the tube 34 is secured a cover plate 37 connecting with the 55 flexible conduit 18. A suitable operating handle is carried by the plate 37 as shown at 38, whose outer surface is milled or roughened to facilitate manipulation.

The method of employing the machine hereinbefore described will largely be understood from the description already presented. The method of forming the matrice in the flask need not specifically be referred to since the same is well understood in the 60 art. When the matrice has been formed, the

flask 10 is ready to be placed on the plate 5 as shown on Fig. 1, and the globule of metal placed on the surface of the matrice in a pocket provided therefor, as usual, and fused by means of a blowpipe or other means 70 so that the fused metal may flow downwardly through a gate into the mold. Just as this operation is about to take place, the carrier 33 is depressed by means of the manually operated handle 38, the cap 36 75 by virtue of its connections as heretofore described, will be forced into sealing relation with the upper edge of the flask 10, before the carrier reaches the downward limit of its movement. This downward pressure of the carrier has also lowered the flask and its supporting plate 5 including the releasing stem 13, adjustably secured to said plate, thus depressing the bar 30 and suddenly releasing the pawl 29, the piston 80 19 within the cylinder 3 is set free to the tension of the coil springs 22 and 22^a driving the said piston upward and forcing the air within the cylinder, by means of the flexible tube 34 into the flask 10 and upon the fused 85 metal. This sudden release is important for the reason that a strong air pressure effect is exerted immediately upon the matrice and the fused metal flows instantly thereinto without possibility of premature solidification. 90

The preliminary operations necessary for using this machine may be performed beforehand that is, the release stem 13 adjusted and the piston 19 drawn to the lower 100 end of the cylinder. It is then only necessary to release the pawl 29, the depressing of the carrier 33 and its sealing cap to close the flask, as well as releasing the pawl 29, being one continuous operation, and permit the air pressure to be exerted through the porous material of the matrice and insure an easy flow thereinto of the molten or fused metal of which the casting is to be made. 110

The cylinder 3 is of relatively large capacity, so that only one stroke of the piston therein is necessary to create a sufficient pressure for one casting operation, thus obviating the continuous pumping operations as in 115 the case of pumps or other means used heretofore.

I am aware that various details of construction may be varied through a wide range without departing from the principles of this invention, and I therefore do not purpose limiting the patent granted otherwise than necessitated by the prior art. 120

What I claim as my invention and desire to secure by Letters-Patent is:

1. A casting machine comprising a base, a cylinder mounted on said base, a cover for said cylinder, an outlet in said cover, a flexible conduit connected to said outlet, a guide arm carried by said cylinder, a tube slidably 130

mounted in said guide arm and connected to said flexible conduit, a cover on said tube, an operating handle secured to said cover, said tube having a flared lower end to form a 5 sealing cap, a flask, a self-adjustable support therefor mounted on said base, a collar within said cylinder, a winding drum, a piston fitting said cylinder and having a piston-band extending through said collar to said 10 drum, a coiled spring interposed between said piston and said collar and adapted when under tension and unrestrained to move said piston in an upward direction, locking means to secure said piston and piston-band in 15 position to the force of said spring, said piston and piston-band when manually moved downward in said cylinder serving to place said spring under tension and said piston when released, so as to move under 20 the action of said spring serving to force air through said flexible conduit and tube into the said flask.

2. In a casting machine comprising a base, a cylinder mounted on said base, a cover for 25 said cylinder, an outlet in said cover, a flexible conduit connected to said outlet, a guide arm carried by said cylinder, a tube slidably mounted in said guide arm and connected to said flexible conduit, a cover on 30 said tube, an operating handle secured to said cover, a coiled spring interposed between said cover and said guide arm surrounding said tube, said tube having a flared lower end forming a sealing cap, a flask, 35 a support for said flask mounted on said base comprising a plate secured on telescoping standards, coiled springs interposed between said plate and the lower parts of the said standards normally urging said plate 40 upwardly, an adjustable releasing means carried by said plate, said operating handle when manually moved downward in said guide serving to place the sealing cap upon said flask and actuating the releasing means, a collar within said cylinder, a winding drum, a piston fitting said 45 cylinder and having a piston-band extending through said collar to said drum, a plurality of coiled spring means interposed between said piston and said collar and adapted when under tension and unrestrained to move said piston in an upward direction, said piston and piston-band when manually moved downward in the said cylinder serving to place said spring under tension, locking means to secure said piston and piston-band in opposition to the force of said spring 50 means, and said piston when released so as to move under the action of said spring means serving to force air through said flexible conduit and said tube into said flask.

3. A casting machine comprising a base, a cylinder mounted on said base, a cover on said cylinder having a flexible conduit, a hollow carrier movably supported by said cylinder and connected to said conduit, a sealing cap on said carrier, a flask supported on said base, said cap being adapted to seal said flask, a piston operating in said cylinder, a plurality of compression means within said cylinder adapted when under tension to move 55 said piston upward, locking means to secure said piston in opposition to the force of said compression means and means for operating said piston to force air from the cylinder into the flask. 70

4. In a casting machine comprising a base, a cylinder mounted on said base, a cover for said cylinder, an outlet in said cover, a flexible conduit connected to said outlet, a guide arm carried by said cylinder, a tube 80 slidably mounted in said guide arm and connected to said flexible conduit, a cover on said tube, an operating handle secured to said cover, a coiled spring interposed between said cover and said guide arm surrounding said tube, said tube having a flared lower end forming a sealing cap, a flask, a support for said flask mounted on said base comprising a plate secured on telescoping 85 standards, coiled springs interposed between said plate and the lower parts of the said standards normally urging said plate upwardly, an adjustable releasing means carried by said plate, said operating handle when manually moved downward in said guide, serving to place the sealing cap upon said flask and actuating the releasing means, a collar within said cylinder, a winding drum, a piston fitting said 90 cylinder and having a piston-band extending through said collar to said drum, a plurality of coiled spring means interposed between said piston and said collar and adapted when under tension and unrestrained to move said piston in an upward direction, said piston and piston-band when manually moved downward in the said cylinder serving to place said spring means under tension, locking means to secure said piston and piston-band in opposition to the force of said spring 95 means, and said piston when released so as to move under the action of said spring means serving to force air through said flexible conduit and said tube into said flask. 100

In testimony whereof I affix my signature in the presence of two witnesses.

SAMUEL J. SYMMONS.
